UNITED STATES PATENT OFFICE

ALONZO P. HENDERSON, OF HANOVER, MASSACHUSETTS

FOLDING STAGING BRACKET

Application filed April 7, 1928. Serial No. 268,184.

The invention has relation to the supporting brackets of builders' staging such as is applied to the exterior of buildings, usually those in the course of construction, to support 5 workers. The brackets in question are those which serve, when in use, to sustain horizontal platforms of planks.

The present invention provides a folding staging bracket of novel and improved constructional character of the type comprising 10 a plurality of members which are connected pivotally to one another and for use are adapted to be arranged in the form of a triangle with two sides thereof rigid and the 15 third jointed intermediate its length. The invention consists further in a folding bracket having combined with the fundamental elements just outlined a hand-rail support as set forth hereinafter.

20 An illustrative embodiment of the invention is shown in the accompanying drawings, in which latter,—

Fig. 1 shows the said embodiment in side elevation, applied to a building wall, the latter being in vertical section, and a platform 25 of planks being shown supported by the bracket.

Fig. 2 shows in plan, on a smaller scale than in the case of Fig. 1, two brackets, a platform 30 of boards resting thereon, and a building-wall in horizontal section.

Fig. 3 is a view in section on line 3, 3, of Fig. 1, the scale being the same as in Fig. 1.

Fig. 4 is an elevation, on different scale, 35 of a bracket in folded condition.

The characteristic elements of the bracket, proper, comprise a platform-supporting member 1, a brace-member 14 which assists in supporting in a horizontal position the 40 said member 1 and the platform resting thereon, and a jointed strut composed of links 17, 19, which is combined with the inner ends of the said members 1 and 14.

In making use of the bracket, the member 45 1, supporting the planking 2 forming the platform upon which the users of the staging may walk about, extends horizontally outward from the wall to which the bracket is applied. In making application of the bracket 50 to the wall, as 3, Fig. 1, the member 1 is

attached to the said wall by means of a fastening bolt 4 which is passed through a hole formed in the wall and through a hole in a cleat 6 extending across two of the studs or uprights 7, 7, behind the wall, the inner end of the bolt having a hand-nut 8 applied thereto at the inner side of the cleat. The upturned outer extremity of bolt 4 is engaged with member 1 by entering it into one of a plurality of holes 12, 12, in the horizontal flange of the said member 1, accidental disengagement 65 of the bolt from member 1 being provided against by means of a cotter-pin 13 occupying a hole through the said extremity above the said flange.

In the relations in which the parts are shown in Fig. 1, the obliquely-disposed brace-member 14 serves, through engagement of its upper end with platform-sustaining member 1 at a distance outward from wall 3, and through contact of its lower end with the said wall, to support the outstanding portion of member 1, together with the load carried by member 1.

The said brace-member 14 is in pivotal or hinge connection with member 1 at a suitable place in the length of member 1, in this instance about two-thirds of its length away from the wall-engaging end. Such hinge-connection is established by means of a pivot 75 15 passing through these members at their meeting-point. To the lower end of brace-member 14 is pivotally attached by means of a pivot 16 the lower end of a flat metal link 17, which is combined at its upper end by a pivot 18 with the lower end of a similar but shorter link-member 19 extending downward from a pivotal connection at 20 with the member 1, the pivots 16 and 20 being located as close as practicable to the wall-engaging 80 85 shoes 5 and 11 of the members 14 and 1. The links 17, 19, constitute the jointed strut to which reference has been made, such strut being in effect a toggle. When the two links are straightened out in line with each other 90 95 as in Fig. 1, so that pivot 18 is in line with pivots 16 and 20, or better still when pivot 18 is caused to occupy a position a little to the left of such line, the said jointed strut serves to maintain the brace-member 14 in fixed 100

relations with respect to platform-sustaining member 1, while the parts are as in Fig. 1, thereby ensuring performance of the bracing function and safeguarding against collapse of the bracket.

The device as thus far described is of a known general character. It constitutes a complete, safe, and very strong bracket. The pivotal or hinge connections, and the relations of the members 1, 14, 17, and 19, enable the bracket to be folded up as in Fig. 4, when detached from wall 3, so that all the members lie parallel and nested together and occupy a very small space. In effecting the folding, it is necessary merely to swing links 17, 19, to the right in Fig. 1 so as to carry pivot 18 in that direction and double-up the said links with each other, which will cause brace-member 14 to approach member 1, thereby nesting members 1, 14, 17, and 19 with relation to one another as in Fig. 4.

The platform-supporting member 1 and brace-member 14 preferably are made of angle-iron or steel. The piece of angle-metal constituting the said platform-supporting member is so related to the associated members of the bracket that in the position occupied by the bracket when in use the top of the said platform-supporting member 1 is constituted by a horizontally-disposed flange, while the other flange extends downward therefrom so as to constitute a vertical side for the member 1. The end of member 1 which is contiguous to the outer surface of wall 3 is provided with a shoe 11 to afford a broad bearing-surface against the said surface of the wall, a hole being cut in the said shoe to permit the stem of the fastening bolt 4 to extend through the shoe. This shoe, in the illustrated instance, is formed by cutting away the metal of one flange of the angle-iron for a short distance and bending the end-portion of the uncut flange at right angles.

The brace-member 14 likewise is constituted of a length of angle metal, with one flange thereof disposed vertically, and the other horizontally. The vertical flange of the said brace-member makes contact with the vertical flange of the platform-supporting member 1 and with one side of the lower link 17. At the lower end of the brace-member 14 the terminal portion of the vertical flange of the angle piece constituting such member is bent at right angles to constitute a broad wall engaging shoe 5 similar to the shoe 11 of the member 1.

In practice, the planking 2 will be supported by means of two or more brackets, as in Fig. 2, spaced conveniently apart. Preferably provision is made for preventing the planking from slipping off the outer end of the bracket or brackets. In the present instance, for this purpose, an upstanding toe 9 is provided at the outer extremity of member 1, conveniently formed by cutting off the

outermost end of the vertical flange of its angle iron and turning up the projecting extremity of the horizontal flange. Also, holes 10, 10, Fig. 2, may be provided in the horizontal flange of member 1 to receive bolts or spikes for holding the planking from endwise movement.

For safety, it is advisable to provide a hand-rail 21 at the side of the staging more remote from the wall to which the staging is attached, and at a suitable height above the planking. At 22, Figs. 1 and 2, is a toe-board of 6 inches or so in width vertically, applied along the outer edge of the staging, adapted to prevent a worker from slipping under the hand-rail and falling, and also to prevent tools from rolling off.

The safety appliances just mentioned are attached to posts, one of which is shown at 26, Fig. 1. In accordance with one part of the invention, a carrier-post 23, constituted of angle iron, is mounted by a pivot 27, located at an intermediate point in the height of the carrier-post, upon the vertical flange of member 1 at the outer end of the member 1. A link-member 24 has one end thereof engaged pivotally at 28 with the member 23 at a point below member 1 and pivot 27, and the other end engaged with the pivot 18 which forms the joint between the link-members 17 and 19, the arrangement being such as to form a parallelogram defined by the member 1, the length of member 23 between its pivotal connection at 27 with member 1 and its pivotal connection at 28 with member 24, the member 24, and the link-member 19. This forms a linkage whereby opening of the bracket into triangular form for application to vertical wall brings the members 23, 26, into vertical position, and places hand-rail 21 and toe-board 22 in working positions. The hand-rail is held very rigidly by this arrangement, as any inward pull, toward the wall, on the hand-rail tends merely to lift the lower end of member 14 vertically upward along the wall, with a consequent slight lifting of the outer side of the whole staging; while an outward push on the hand-rail tends to force the inward end of member 24 more firmly against the unyielding surface of the wall with no result except that a very great force will likewise cause a slight lifting of the outward side of the staging.

When the bracket is folded, after detachment of the hand-rail and toe-board, the members 23 and 24 fold together into exact parallelism with member 1.

What is claimed as the invention is:—

1. A folding wall bracket comprising a plurality of members arranged in a triangle of which two sides are rigid and the third jointed intermediate its length and in combination therewith, a hand-rail, and a hand-rail-supporting member which is pivotally combined with one of said members and con-

nected by an additional member to the joint in said third side.

2. A folding wall bracket comprising a member adapted to be affixed to a wall so as to extend out horizontally therefrom, a member pivotally combined with said member to extend obliquely downward to contact with said wall, two members pivoted to each other and to the wall-engaging ends of the first two members to lie parallel to the wall, and all combined to form a foldable triangle, a hand-rail-supporting member pivotally combined with the first-mentioned member and a member connecting the said hand-rail supporting member to the pivot joining the two wall-paralleling members, all the members being foldable into substantially parallel relation to each other without disconnection of joints when detached from the wall.
